UNITED STATES PATENT OFFICE.

FRANK G. BARKOW, OF LOS ANGELES, CALIFORNIA.

GAME.

1,253,202.

Specification of Letters Patent. Patented Jan. 15, 1918.

Application filed March 1, 1917. Serial No. 151,683.

To all whom it may concern:

Be it known that I, FRANK G. BARKOW, a citizen of the United States, residing at Los Angeles, in the county of Los Angeles 5 and State of California, have invented new and useful Improvements in Games, of which the following is a specification.

This invention relates to a game.

It is an object of this invention to provide 10 a game which may be played by one or more players and which is so arranged as to permit various scores to be obtained by the players by chance.

Another object of this invention is to provide 15 a game of the above character which may be played without possibility of any of the players influencing the scoring members of the game in a manner to alter their course of travel or cause them to move in 20 a particular direction.

It is a further object to provide a game board which will act in an automatic manner to release scoring members consecutively and individually without manipulation 25 by one of the players, said board being simple in its construction and operation.

Other objects will appear hereinafter.

The invention is illustrated by way of example, in the accompanying drawings in 30 which:

Figure 1 is a view in plan elevation illustrating the game board and disclosing the board and the scoring means mounted thereupon.

Fig. 2 is a view in side elevation illustrating the game board particularly disclosing the compartment and mechanism for holding and releasing the scoring elements.

Fig. 3 is a view in end elevation with 40 parts broken away illustrating the game board and particularly disclosing the runways provided for the scoring elements and the release mechanism therefor.

Fig. 4 is a view in section and elevation 45 as seen on the line 4—4 of Fig. 3 illustrating the release mechanism and the manner in which it is automatically actuated by the scoring elements.

Referring more particularly to the drawings, 50 10 indicates a substantially horizontal board which is bounded along its opposite sides by vertically extending flanges 11 and 12. The forward end of the board is closed and is fitted with a series of parallel compartments 13. These compartments are arranged across the foot end of the board in 55

parallel relation to each other and are here shown as consecutively numbered from one to twelve. The opposite or head end of the board is fitted with a vertical superstructure 60 14. This structure is provided as a receptacle and a run-way for scoring elements 15. The run-way is formed of channels which are arranged in zig-zag relation across the end of the board and beneath each other, as 65 shown in Fig. 3 of the drawings. Openings 16 are formed in the floor of each channel at its lower end so that the elements may fall through and pass along the underlying channel which lies in diagonal relation thereto. The upper channel of the structure is provided as a receptacle for the scoring elements, here shown as marbles. 70

The scoring elements are retained in the channel at the top of the superstructure by 75 means of a finger 17. This finger is adapted to be automatically actuated by the movement of the marbles, to release marbles from the compartment and permit them to run along the run-ways. This is accomplished by means of a detent 18 which is pivotally mounted upon a pivot bolt 19 and is fixed to move with the finger 17. This detent hangs downwardly into a trough 20 along which the marbles finally pass from 80 the run-ways on the game board. The detent is weighted and, as the marble passes along the trough, is raised to swing the finger in the direction indicated by the arrow —a—. This will release a marble 85 from the top run-way, after which the finger will fall in place to hold the remaining marbles.

The trough 20 is shown in the preferred construction as placed at one side of the 95 game board and in communication with a chute 21 leading to the center of the board. Mounted upon the board and positioned between the mouth of the chute and the compartments 13 is a series of obstructor pins 100 22. These pins are arranged in rows and the individual pin members are staggered in relation to each other. A sufficient distance occurs between the pins to allow the marbles to pass at random between the pins and 105 finally come to rest within one of the compartments, thereby registering a score.

When the game is to be played, a number of marbles is positioned at the top of the run-way and held by the finger 17. When 110 the game is started, one of the marbles is released from the top of the run-way and

2
allowed to pursue its zig-zag course of travel down to the board. When it reaches the bottom of the trough along which it passes it will lift the detent and cause the finger 5 to be swung out of an obstructing position, thus permitting one of the marbles to be released, after which the weight of the detent will swing the finger back in position until again actuated by the marble previously 10 released. The marbles will roll out upon the game board and down the inclined floor among the pins 22, after which they will finally come to rest within the compartments. In this manner the game will be 15 played without possibility of manipulation of the scoring elements by the players and the result of the game will therefore be entirely a matter of chance.

It will thus be seen that the game here 20 disclosed is simple in its construction and operation and may be easily played and that it may be built in a substantial manner.

While I have shown the preferred construction of my game as now known to me, 25 it will be understood that various changes in the combination, construction, and arrangement of parts may be made by those skilled in the art without departing from the spirit of my invention.

30 I claim:

1. A game comprising a horizontal board having flanges extending along its sides, means forming a series of parallel compartments at the foot of the board, a frame extending upwardly at the head of the board, 35 an inclined ball receptacle at the top of the frame across the end of the board, channels forming a zig-zag run-way from the lower end of the ball receptacle to near the bottom of the frame; there being an opening

in the lower end of each channel discharging into the head of the next channel and there being an opening in the lower end of the receptacle discharging into the head of the first channel; a pivoted finger extending 45 across the lower end of the receptacle to hold the balls in the receptacle, a trough leading from the lower end of the lower channel; said trough discharging to the board; and a detent extending from the pivoted finger into said trough; said detent and finger forming an escapement so that when started the passage of a ball along the trough will operate the detent to operate the finger to release another ball. 55

2. In a game, a board, a frame extending upwardly from the board, a receptacle mounted at the top of the frame and having a discharge opening; the floor of the receptacle being inclined toward the opening; a series of channels mounted in the frame one above the other; said receptacle discharging to the upper end of the series of channels and said channels being inclined, the lower end of one channel discharging to the head of the next one, and there being an outlet at the lower end of the series discharging to the board; and a lever pivotally mounted with one end in position to hold balls in the receptacle and the other end in position to be operated by a ball passing to the board; so that when the device is started and the receptacle filled with balls the passage of a ball to the board will operate the lever to release the next ball, and the device will continue to operate until the stock of balls is exhausted. 60 65 70 75

In testimony whereof I have signed my name to this specification.

FRANK G. BARKOW.
